[57] CLAIM

The ornamental design for an open top packaging container, as shown and described.

DESCRIPTION

FIG. 1 is a top perspective view of an open top packaging container embodying my new design;

FIG. 2 is a side elevational view;

FIG. 3 is a side elevational view with the open top packaging container rotated 45° from the position of FIG. 2;

FIG. 4 is a top plan view;

FIG. 5 is a bottom plan view;

FIG. 6 is a top perspective view showing a modified form of my new design;

FIG. 7 is a side elevational view;

FIG. 8 is a side elevational view with the open top packaging container rotated 30° from the position of FIG. 7;

FIG. 9 is a top plan view;

FIG. 10 is a bottom plan view; and

FIG. 11 is a fragmentary longitudinal sectional view taken through the bottom part of FIG. 3.
